UNITED STATES PATENT OFFICE.

CORNELIUS GEORGE NOBBS AND WALTER WILLIAM NOBBS, OF LONDON, ENGLAND.

ELECTRICAL HEATING AND COOKING APPARATUS.

1,345,222.

Specification of Letters Patent. Patented June 29, 1920.

Application filed December 26, 1918. Serial No. 268,310.

To all whom it may concern:

Be it known that we, CORNELIUS GEORGE NOBBS and WALTER WILLIAM NOBBS, both subjects of the King of Great Britain, both 5 residing in London, England, have jointly invented certain new and useful Improvements in Electrical Heating and Cooking Apparatus, of which the following is a specification.

10 In our prior British specification No. 12,318 of 1915 an electric heating apparatus for immersion in liquids is described in which heating conductors in the form of wires or strips were wound on flat strips of 15 mica or other suitable insulating supports and when externally covered by similarly shaped strips of mica or the like were inserted in an outer protecting cover of copper or other suitable material, preferably, of 20 elliptical cross section. After the insertion of the heating coil the cover was compressed into a flat tubular form with rounded edges and incurved sides in order to insure intimate heat conducting contact between the 25 inclosed parts and the outer cover.

The current was led to a central conductor in the form of a strip of the same width as the insulating supports between which it was inclosed and returned by a wire or 30 strip wound on the flat insulating strips. In one form of the invention the central conductor was connected to two wires wound separately on insulating strips and inclosed in the same protecting cover.

35 According to the present invention, which consists in modifications or improvements of the constructions described in the prior specification, the mica or other insulation, placed between the conducting wires or 40 strips and the metal cover, is protected against damage, which is liable to occur during the process of compressing the outer envelop and inserting or removing the heating element, by the interposition of a metal 45 sheath between the insulation and the cover.

The ends of the protecting envelop are, preferably, reduced in longitudinal section to a form which tends to prevent the formation of eddy currents and lessens the resistance to the circulation of the fluid in which 50 the heating device is immersed.

The block to which the leading in terminals are secured is placed at the top or bot-

tom side instead of at the end of the heater, also, in order to facilitate the flow of fluid 55 past the heater.

In the accompanying drawings which represent an example of a construction according to the invention, Figure 1 is a sectional elevation of the heater immersed in the 60 liquid to be heated;

Fig. 2 is a section on the line 2—2 of Fig. 1;

Fig. 3 is an elevation on a larger scale of the heater, with part of the cover removed; 65

Fig. 4 is a plan view as seen from below and Fig. 5 is a cross section of the heater.

The heating element comprises a wire or strip 1, preferably, of nickel chromium (ni-chrome) wound around insulating supports 70 2 and 3 of mica. In the example shown the conductor 1 is connected with one of the leading in terminals 4 and 5 and after being wound spirally around one of the insulating supports 2 or 3 to the end of the heating 75 element returns by a similar spiral winding around the other insulating support to the other terminal. A central strip 6 of mica insulates the adjacent windings of the conductor. Strips 7 and 8 of mica insulate the 80 conductor from a cover 9 and from a metal sheath 10, which is inserted between the mica insulation 7 and 8 and the cover; in order, as explained above, to prevent any damage occurring to the mica insulation 85 during its insertion in or removal from the cover 9 or the process of compressing the cross section of the cover from a circular or elliptic form into a flattened and slightly incurved section with rounded edges as 90 shown in Fig. 5, the sheath 10 is of tubular form as shown by the dotted lines in Fig. 4, the resistor being inserted through the open ends of the tube before the latter is placed within the cover 9. As described in the 95 prior specification this form maintains all the parts of the heating element in intimate contact and insures good thermal conductivity with the outer envelop.

The invention is not limited to the arrangement in which the conductor is wound around two insulating supports in series as shown in Fig. 5; other arrangements of the conducting wire may be employed, such as the single insulating support shown in the 105 prior specification referred to. Also, al-

though mica has been described as the insulating medium other suitable material may be employed for the purpose.

The ends 11 and 12 of the cover 9, beyond 5 the limits of the conducting wire and its supports, are reduced in section to the form shown in order to facilitate the flow of the circulating liquid in the vessel or conduit in which the heating element is immersed.

10 The connection with the leading in terminals is made at the lower side of the element as shown in Figs. 1, 3 and 4. In the example illustrated a saddle shaped member 13, conforming to the internal surface of 15 the vessel or conduit 15 in which the heating element is to be immersed, is soldered to the cover 9; a rubber seating 14 being interposed between the member 13 and the surface of the vessel. A block 16 of ebonite or 20 other insulating material is secured to the member 13 by screws 17. The leading in wires 18 of the heating conductor 1 are brought into the hollow bases of the terminal sockets 4 and 5 and are secured by set 25 screws 19 and 20.

The arrangement according to the invention is adapted generally for use in electric heating and cooking apparatus and is also especially applicable for warming the water 30 for radiators for internal combustion engines in cases where such water is liable to freeze, as when the engines have been shut down and the radiators are exposed to very low temperatures. Such conditions are 35 especially likely to occur, as is well known, in the working of aeroplane engines.

Having thus described the nature of the 40 said invention and the best means we know of carrying the same into practical effect, we claim:—

1. An electric heating device of the immersion type comprising in combination a flat strip of insulating material, a conductor wound thereon, insulating strips in contact with either surface of said conductor, 45 a metal sheath open at the longitudinal sides extending above and below over the whole breadth of the conductor and a protecting

cover inclosing the whole and pressed into intimate contact with said sheath, the said 50 protecting cover being in direct contact with the liquid to be heated.

2. An electric heating device of the immersion type comprising in combination a flat strip of insulating material, a conductor 55 wound thereon, insulating strips in contact with either surface of said conductor, a metal sheath open at the longitudinal sides extending above and below over the whole breadth of the conductor and a protecting 60 cover with rounded edges and incurved sides inclosing the whole and pressed into intimate contact with said sheath.

3. An electric heating device of the immersion type comprising in combination a 65 flat strip of insulating material, a conductor wound thereon, insulating strips in contact with either surface of said conductor, a metal sheath protecting said conductor and said insulating strips, a protecting cover, a 70 saddle shaped member embracing said cover and conforming to the shape of the vessel in which the heating device is immersed, an insulating seating between said member and the vessel, an insulating block secured 75 by screws to said member, and hollow terminal sockets on said block in which sockets the ends of the conductor are secured.

4. An electric heating device of the immersion type comprising in combination a 80 flat strip of insulating material, a conductor wound thereon, a second flat strip of insulating material on which a continuation of the said conductor is wound, a strip of insulating material placed between the strips 85 on which the conductor is wound and strips of insulating material on either side of the conductor, an outer protecting cover and a metal sheath between said cover and the insulating strips provided on either side of the 90 conductor.

In testimony whereof we have signed our names to this specification.

CORNELIUS GEORGE NOBBS.
WALTER WILLIAM NOBBS.
